UNITED STATES PATENT OFFICE

140,109

DESIGN FOR A COMBINED PERFUME SACHET HOLDER AND PENDANT

Franklin Pierce, New York, N. Y.

Application October 16, 1944, Serial No. 115,807

Term of patent 7 years

(Cl. D86—10)

To all whom it may concern:

Be it known that I, Franklin Pierce, a citizen of the United States, residing at New York, in the county of New York and State of New York, have invented a new, original, and ornamental Design for a Combined Perfume Sachet Holder and Pendant, of which the following is a specification, reference being made to the accompanying drawing, forming a part thereof, in which

Figure 1 is a bottom perspective view of a combined sachet holder and pendant in open position, embodying my new design;

The dominant features of the design reside in the portions shown in full lines.

I claim:

The ornamental design for a combined perfume sachet holder and pendant, as shown and described.

FRANKLIN PIERCE.
